UNITED STATES PATENT OFFICE

ROY N. PURDY, OF SAN ANTONIO, TEXAS

HINGE

Application filed October 15, 1929. Serial No. 399,763.

This invention relates to a hinge designed primarily for use in connection with doors, one of the objects being to provide a hinge so constructed as to prevent a door from swinging freely and to insure its remaining, under ordinary conditions, at any point to which it might be moved.

Another object is to provide a hinge which can be applied in the same manner as an ordinary hinge, no special mortising being required.

A further object is to provide a hinge that is adjustable to vary the friction produced by the several parts.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is an elevation of the hinge.

Figure 2 is a section on line 2—2, Figure 1, the combined bolt and pintle being shown in elevation.

Referring to the figures by characters of reference, 1 designates one of the leaves of the hinge, the same being provided with knuckles 2 spaced from each other and inwardly from the ends of the leaf. The space between the knuckles 2 is adapted to receive a knuckle 3 extending from a leaf 4. This leaf 4 is shorter than the leaf 1 so that smaller

leaves 5 can be arranged adjacent the ends thereof, each of the smaller leaves having a knuckle 6 adapted to bear against the outer end of the adjacent knuckle 2. All of the knuckles aline as ordinarily and are adapted to receive a pintle in the form of a bolt 7.

The head 8 of the bolt bears against a resilient split washer 9 mounted on one of the knuckles 6 while the other end of the bolt, which is screw-threaded as shown at 10, is adapted to be engaged by a nut 11 bearing 50 against a resilient split washer 12 engaging the adjacent knuckle 6.

When the knuckles are in contact as shown in Figures 1 and 2, the leaves 5 are slightly spaced from the leaf 4. Leaves 1 and 4 have 55 openings 13 for the reception of fastening screws or the like. The leaves 5 have short slots 14 therein for the reception of fastening screws or the like whereby these leaves can be adjusted toward or from the leaf 4. 60

It is to be understood that the leaf 1 is to be attached to a door while the leaves 4 and 5 are to be attached to a door frame although this arrangement may be reversed, if desired. By means of the nut 11 the bolt 7 can be adjusted to place the washers 9 and 12 under compression so that they will cause the knuckles 6 to bind tightly against the knuckles 2. Thus the swinging movement of the leaf 1 relative to the leaves 4 and 5 will 70 be retarded and a door provided with hinges such as described, will not swing freely but will, under ordinary conditions, remain in any position to which it might be swung. 75

It will be understood that this hinge can be applied as readily as any ordinary hinge but is advantageous compared therewith because it retards the swinging of a door and therefore prevents slamming or free back and forth swinging. 80

While the hinge is especially designed for use in connection with doors, it can also be used for connecting lids to desks, boxes and other containers.

What is claimed is:

A hinge including an intermediate and end leaves disposed in the same plane and spaced apart, knuckles extending from said leaves and disposed in alignment, the end hinge leaves having transverse fastener receiving 90

slots, a single leaf having knuckles interposed between and aligning with the knuckles of the first mentioned leaves, a pintle extending through all of the knuckles, and an adjustable resilient means on the end portions of the pintle for exerting a constant thrust against the outer ends of the knuckles of the end leaves to bind said knuckles upon the adjacent knuckles of said single leaf.

10 In testimony that I claim the foregoing as my own, I have hereto affixed my signature.

ROY N. PURDY.
